UNITED STATES PATENT OFFICE

PER HEIBERG, OF NOGALES, ARIZONA

COMBINATION BATH TOWEL

Application filed November 24, 1928. Serial No. 321,636.

This invention relates to new and useful improvements in bath towels and aims to provide a combined Turkish towel and hand towel, that is a towel so woven as to provide a loosely woven or Turkish area, and a tightly woven or smooth area. Obviously therefore a towel of this type can be employed for all purposes of the Turkish towel and at the same time be used for all purposes of the smooth or hand towel.

In the drawing wherein like numerals indicate corresponding parts throughout the same:

Now having particular reference to the 20 drawing, 5 designates generally a towel of predetermined length and width. The major area of the towel is woven to provide a Turkish surface, the longitudinal or warp threads being loose as is usual in this type of 25 towel this surface being indicated by the reference character 6. However, in carrying out the present invention certain predetermined areas adjacent opposite ends of the towel 5 are formed by tightly woven threads with 30 smooth or hand towel areas 7—7. It is to be of course understood that I do not desire to be limited to any particular relationship of the smooth or hand towel area or areas with respect to the towel unit as it is obvious 35 that the towel can be so woven as to provide one or more smooth or tightly woven areas and at any predetermined point throughout the length or width of the towel body.

Having thus described the invention, what 40 I claim as new and desire to secure by Letters Patent is:

In a combination towel of the character described, a length of fabric of elongated rectangular configuration wherein a certain portion 45 of the fabric inwardly from opposite ends thereof is tightly woven to provide on opposite faces of the towel a pair of relatively large smooth plain areas, and the remaining portion of the fabric being loosely 50 woven to provide on opposite sides thereof a Turkish effect the major portion of the loosely woven area being between the two plain areas and of a greater width and breadth than either of the latter areas of the towel, and each of said plain areas being encompassed by certain remaining loosely woven portions of the fabric.

In testimony whereof I affix my signature. PER HEIBERG.
